VENETIAN BLIND

Siegfried F. Mayer, Lock Haven, Pa., assignor to
 May-Sloan Inc., Mill Hall, Pa., a corporation
 of Pennsylvania

Application February 13, 1948, Serial No. 8,205

4 Claims. (Cl. 160—173)

1

The present invention relates to Venetian blinds and aims generally to improve the construction of existing blinds of that type.

A primary object of the invention is the provision of an improved Venetian blind of the metal or flexible slat type, in which the slats are readily removable from the blind for cleaning and replacement.

A further object of the invention is the provision of an improved Venetian blind construction which will be of pleasing appearance as well as of simple construction and of economical cost of manufacture.

Other aims and objects of the invention will be apparent to persons skilled in the art to which the invention relates from a consideration of the accompanying drawings and annexed specification illustrating and describing a preferred form of the invention.

In the drawings—

Fig. 1 is a perspective view of a portion of a Venetian blind construction illustrating particularly the construction and arrangement of the base bar, tapes, elevating cord and slat therefor;

Fig. 2 is a similar view illustrating the manner of removing or inserting a slat in the blind;

Fig. 3 is a vertical sectional view of the blind as taken in the plane of the elevating cords;

Fig. 4 is a horizontal sectional view as taken on the line 4—4 of Fig. 3; and

Fig. 5 is an end elevation of the portion of the blind shown in Fig. 1.

Referring to the drawings, the Venetian blind of the invention comprises a base bar or bottom rail 10, of suitable length to fit between the side rails of a window frame in which the blind is used, and which advantageously may comprise a pair of opposed angularly bent plates secured in assembled relation as by means of a screw or nail 11, said base bar 10 being suspended from an upper rail (not shown) by means of elevating cords 12, as is usual in the art. As illustrated, the base bar or bottom rail may be formed of tubular sheet metal construction, and has sufficient weight to insure that the blind will hang evenly.

The lower terminal ends of the elevating cords 12 are suitably secured to the base bar 10 adjacent the ends thereof, and preferably are secured thereto inwardly of the terminal ends of the bar 10, a distance not greater than the width of the bar.

2

The base bar 10 is further suspended from the side rail by the usual fabric tapes 13 and 14 disposed on opposite sides of the bar and connected at their lower ends thereto as by being clamped between the opposed plates comprising the bar 10. The tapes 13 and 14 are disposed on opposite sides of the elevating cords, and thus are disposed adjacent the end of the bar to enhance the attractive appearance of the blind. The tapes 13 and 14 are of the ladder type, being interconnected by means of a plurality of vertically spaced slat-supporting cross tapes or webs 15 of the textile material, secured as by stitching 16 to the inner faces of the tapes 13 and 14. The cross tapes 15 are of less width than the tapes 13 and 14, and at least some of them are secured to the tapes 13 and 14 adjacent the outer edges thereof, so as to be disposed outwardly of the elevating cords 12. This insures proper alignment of the tapes and slats relative to the elevating cords 12. As herein illustrated, alternate tapes 15 may be secured to tapes 13 and 14 along opposite edges so as to be staggered on opposite sides of the cords 12.

The slats 20 of the blind are preferably formed of the usual metal Venetian blind slats, being of a length approximately equal to the base bar 10, and either of flat or slightly convexed cross section, as desired. Such metal slats are conventionally formed of sheet metal of approximately 0.010 inch in thickness and are highly flexible both longitudinally and transversely.

The end portions of the slats 20 are slotted for a short distance approximately equal to one-half the width of the slat to receive the elevator cords 12. Such slotted portion includes a restricted longitudinal slot 21 open at the ends of the slats and a transverse cord guideway 22 of substantially greater width than the slot 21. Preferably, the combined slots may be T-shaped, the guideway portion 22 being of suitable length and width to permit free tilting and raising and lowering of the slats relative to the cords 12. The slot 21 is preferably much narrower and substantially less in width than the diameter of the cord 12. Due to the flexibility of the material of the slat 20, the end portions on opposite sides of the slot 21 readily separate to permit the cord 12 being passed therethrough, as is illustrated in Fig. 2.

To facilitate entry of the slats 20 between the

tapes 13—14 and around the cords 12, the corners, between the sides and ends as well as between the ends and sides of the slot 21, are rounded as at 23.

As will be apparent from Fig. 1, the ends of the slats 20 rest loosely on and are supported by the cross webs 15. Being of flexible sheet material, they are readily bendable along a transverse line intermediate their ends to shorten the effective length of the slats 20 and permit the slotted end portions thereof to be pulled past the cords 12 to remove the slats from the blind. In this action the resilient end portions on opposite sides of the slots 21 readily flex outwardly to permit passage of the cord 12 therethrough without deforming the shape of the slat.

From the above it will be seen that the invention provides a Venetian blind of extremely simple construction and which may be economically manufactured. The slats may be quickly and easily removed from the blind while the blind is in lowered position and between the side rails of a window frame. The disposition of the supporting tapes 13 and 14 at the terminal ends of the blind and on opposite sides of the cords 11 enhances the attractiveness of the blind.

The present application is a continuation in part of my prior copending application Serial No. 662,783, filed April 17, 1946, now abandoned.

Although I have illustrated and described a preferred embodiment of the invention, I do not intend to be limited to the specific details thereof as the scope of the invention is best defined in the appended claims.

I claim:

1. A Venetian blind comprising a horizontally disposed base bar, a pair of elevating cords each secured at one end to said base bar adjacent an end thereof, a pair of tapes secured to said base bar adjacent opposite ends thereof and having portions disposed on opposite sides thereof in transverse alignment with said cords, a plurality of vertically spaced transverse slat-supporting webs disposed between opposed portions of each tape at least some of which are disposed outwardly of said elevating cords and a plurality of slats of flexible sheet material having longitudinally slotted ends supported on said webs, the slotted ends of said slats including an end opening longitudinal slot of less width than said cord and an angularly disposed cord-receiving guide, the end portions of said slats opposite said end opening longitudinal slots being flexible, said flexible slats being transversely bendable intermediate their ends to permit movement of the longitudinally slotted end portions thereof past said elevating cords.

2. A Venetian blind having removable flexible sheet metal slats comprising a base bar, a pair of elevator cords having one end secured to said bar adjacent opposite ends thereof, a pair of opposed tapes secured to opposite end portions of said bar, a plurality of vertically spaced supporting webs interconnecting the opposed tapes

of each pair and disposed adjacent to and outwardly of said cords, and a plurality of flexible sheet metal slats supported adjacent their ends on said webs, the end portions of said slats including a longitudinal slot of less width than said cord extending inwardly from the ends of said slats and an enlarged cord-receiving opening at the inner end of said slot.

3. A Venetian blind comprising a horizontal weight providing base bar, a pair of ladder-tapes connected at their lower ends to one end portion of said base bar, the outer vertical edges of the tapes being adjacent the end portions of said bar, a lifting and lowering cord connected at its lower end to the end portion of said base bar and extending upwardly between said ladder-tapes, a plurality of cross-tapes between said ladder-tapes and defining supporting steps for adjacent end portions of insertable and removable slats, and bendable sheet metal slats each having a keyhole slot in one end thereof, said slotted one end being adapted to rest on the cross-tape and said slat being attachable to said cord by way of the slot, at least some of said cross-tapes disposed outwardly of said cord preventing accidental displacement thereof from said slot.

4. A Venetian blind comprising a freely hanging heavy metal horizontally disposable base bar made up of complementary sections, a pair of ladder-tapes connected at their lower ends to one end portion of said base bar, the outer vertical edges of the tapes being adjacent the end portions of said bar, a lifting and lowering cord connected at its lower end to the end portion of said base bar and extending upwardly between said ladder-tapes, a plurality of cross-tapes between said ladder tapes and defining supporting steps for adjacent end portions of insertable and removable slats, said cross-tapes being disposed outwardly of and adjacent said cord, and a plurality of thin steel slats having keyhole shaped slots in their end portions, said slats being bendable whereby said end portions may be inserted between the ladder-tapes to rest on the cross-tapes and said keyhole shaped slots releasably engaged with said cord, said cross-tapes preventing accidental dislodgment of said cord from said keyhole slot.
